UNITED STATES PATENT OFFICE.

PHILIS MAYOTTE, OF ESCANABA, MICHIGAN.

SASH FASTENER AND LOCK.

Application filed September 18, 1923. Serial No. 663,441.

To all whom it may concern:

Be it known that I, PHILIS MAYOTTE, a citizen of the United States, and a resident of Escanaba, in the county of Delta and State of Michigan, have invented a new and Improved Sash Fastener and Lock, of which the following is a full, clear, and exact description.

This invention relates to locking mechanisms for windows and the like and particularly to an improved sash fastener and lock wherein the sash is normally maintained locked but the parts are so positioned and arranged that by a slight manipulation, the sash may be readily moved to any desired position.

Another object of the invention is to provide an improved sash fastener and lock wherein there is provided an improved locking mechanism adapted to automatically move to a locked position whenever released.

A still further object of the invention is to provide a sash lock wherein an improved structure is presented that is comparatively small and formed to be readily embedded in the window frame at substantially any point.

In the accompanying drawing—

Figure 1 is an elevation of a window frame and a pair of sashes, certain parts being broken away for better illustrating the fastener and lock applied thereto.

Figure 2 is an enlarged fragmentary transverse sectional view through Figure 1, approximately on line 2—2.

Figure 3 is a sectional view through Figure 2, approximately on line 3—3.

Referring to the accompanying drawing by numerals, 1 indicates a frame of any desired kind which is provided with sashes 2 and 3 of any desired or preferred kind. Each of these sashes is formed with a cut-away portion 4 adapted to accommodate a rack 5 formed with teeth 6 designed to be continually in mesh with the gear 7. As the sashes 2 and 3 are of identical construction and also the locking mechanisms in connection therewith are identical, the description of one will apply to both.

As shown particularly in Figures 2 and 3, the gear 7 and certain other parts are arranged in a casing 8 formed preferably of sheet metal, said casing including an inner plate 9 having an opening 10 through which part of the gear wheel 7 projects. Suitable securing screws 11 extend through plate 9

and through flanges 12, said screws engaging part of the frame 1 whereby the casing 8 is rigidly secured to the frame.

From Figures 1 and 2 it will be noted that the casing 8 and associated parts are arranged within the frame and that merely the rod 13 extends therethrough, said rod having a button or enlargement 14 fitting into a suitable recess 15. The rod 13 is preferably threaded into a centering pin 16 which is provided with a flange 17 for receiving the spring 18, which spring surrounds the pin 16. The pin 16 is provided with a round restricted connecting portion 19 merging into a square portion 20. The spring 18 and certain other parts are positioned in the bore 21 of the hub 22 of gear wheel 7. The gear wheel 7 is also provided with a central depression 23 for receiving the boss or enlargement 24 of casing 8, which boss or enlargement is formed with a square aperture 25 registering with the square aperture 26 formed in the gear wheel 7. The spring 18 normally holds the parts in the position shown in Figure 2 whereby the square section 20 fits into the square apertures 25 and 26 and, consequently, locks the gear wheel 7 against rotation. When the gear wheel 7 is locked against rotation, it will positively hold the sash in the position in which it is at that time and acts as a lock therefor.

If the sash is entirely closed, it will be locked closed or if it is partially open, it will be locked in that position and held against movement until the thumb member or button 14 is pressed for forcing the round section 19 into the square aperture 26 whereupon gear wheel 7 is released and, consequently, may freely rotate as the sash is moved upwardly or downwardly. As soon as the button 14 is released, spring 18 will move back to the position shown in Figure 2 and, consequently, part of the square section 20 will enter the square opening 26 and lock the gear wheel 7 against rotation and in this manner lock the sash against movement in either direction. It will be noted from Figure 1 that the only parts which are seen are the buttons 14 and possibly a little of the gear teeth 6 on the respective racks 5.

What I claim is:—

1. A window sash fastener and lock, comprising a rack adapted to be secured to a sash, a gear wheel meshing with said rack

- provided with a comparatively long hub formed with a bore extending almost entirely therethrough and with a square aperture merging into said bore, a casing formed with a square aperture in line with the square aperture of the gear wheel, a manually actuated rod extending axially through said bore and through said apertures, said rod being squared to fit said square apertures, 5 said rod having a connecting section adjacent the square part of a diameter not greater than the greatest diameter of the square part, and a spring acting on said manually actuated member for holding 10 said square sections normally engaging the square apertures in the casing and gear wheel, said manually actuated member being adapted to be moved manually so that the connecting section will fit into the 15 square aperture of the gear wheel whereby the gear wheel may rotate as the sash and rack are moved.

2. A combined sash fastener and lock, comprising a rack secured to the sash, a gear

meshing with said rack provided with a 25 comparatively long hub, said hub having a depression on one face and a bore extending from the opposite face toward the depression, and a polygonal-shaped aperture connecting said bore and said depression, a 30 supporting member formed with a boss fitting into said depression, said boss having a polygonal-shaped opening of the same shape and size as the polygonal-shaped opening in said hub, a square reciprocating 35 member fitting into said polygonal-shaped openings for locking the hub and the casing together, said reciprocating member having a reduced section of a diameter not greater than the smallest diameter of the polygonal- 40 shaped part of the reciprocating member whereby it may be forced into the polygonal-shaped opening of the hub and thereby permit a rotation of the gear wheel as the sash is moved upwardly and downwardly.

PHILIS MAYOTTE.
